UNITED STATES PATENT OFFICE.

JOHN MACLURE, OF NEWARK, NEW JERSEY, ASSIGNOR TO HIMSELF, SAM'L. E. TOMPKINS,
AND S. C. NORTHRUP, OF SAME PLACE.

MACHINE FOR COVERING SADDLETREES.

Specification of Letters Patent No. 25,867, dated October 18, 1859.

To all whom it may concern:

Be it known that I, JOHN MACLURE, of Newark, in the county of Essex and State of New Jersey, have invented a new and useful 5 Machine for Covering Seats of Saddletrees; and I do hereby declare that the following is a full, clear, and exact description of the same, reference being had to the annexed drawings, making a part of this specification, in which—

Figure 1, is a longitudinal vertical section of my invention taken in the line x, x , Fig. 3. Fig. 2, a transverse vertical section of ditto, taken in the line y, y , Fig. 3. Fig. 3, 15 a plan or top view of ditto. Fig. 4, is a vertical central section of a saddle tree with its seat covered. Fig. 5, is a detached inverted perspective view of the cover of a seat. Fig. 6, is a longitudinal section of 20 the same. Fig. 7, is a detached perspective view of a seat. Figs. 8 and 9 are perspective views of saddle trees showing the old method of covering the seats.

Similar letters of reference indicate corresponding parts in the several figures.

The object of this invention is to facilitate and expedite the covering of the seats of saddle trees, work which has hitherto been done manually at an expenditure of 30 time and labor that involved considerable expense, requiring skilful and tasty workmen to perform even passably good work.

To enable those skilled in the art to make and use my invention I will proceed to describe its operation and construction.

A, represents a bed piece, in or to which a metal box B, is attached. This box may be of semi-cylindrical or approximate form, and a recess C, is formed in it over which 40 a cushion D, is secured by plates a, a . This cushion is of india-rubber or other suitable elastic material.

Within the recess C, at its upper part, there are two sliding bars E, E, one at each 45 side of the recess, and directly underneath the cushion D, as shown clearly in Fig. 2. These sliding bars E, E, work on horizontal bearing surfaces b, b , in the recess C, and they are operated by screws F, F, which pass 50 horizontally through the box B, work in female screws therein and have their inner ends attached to the bars E, as shown at c.

G, is a lever the fulcrum pin d , of which passes through a standard H, on the bed-piece A. Through the outer end of this 55 lever G, a screw I, passes, the lower end of which is fitted in a step e. The inner end of the lever projects over the cushion D.

The operation is as follows:—The seat J, Fig. 7, is detached from the tree K, see Figs. 4, 8 and 9, and the cover L, Fig. 5, is made to suit the seat J, the parts forming the cover being cut out and sewed together previous to using the machine. The seat J, is then placed within the cover L, the latter being 60 moistened, and the seat is placed in an inverted position on the cushion D. The inner end of the lever G, is then, by operating screw I, forced down on the seat J, and the latter is pressed down within the cushion D, 65 which, owing to its elasticity, stretches the cover L, snugly over the seat J, the seat J, being forced down until such result is attained. When the cover L, is perfectly fitted or stretched over the seat J, the operator 70 by turning the screws F, F, moves the bars E, E, toward each other and the upper edges of the cover L, are folded over the sides of the bottom of the seat J, and a metal plate or clamp K', is screwed to the bottom of the 80 seat to retain the edges of the cover L. The lever G, is then, by actuating the screw I, raised at its inner end and the covered seat removed, the plate or clamp K', remaining 85 attached to the seat until the cover L, is dry, when the plate or clamp K', is removed and the seat attached to the tree by the screw f, as usual.—See Fig. 4.

By this invention the tedious hand operation is entirely dispensed with, and the covers L, may be fitted more perfectly to the seats than by the old mode of covering, as shown in Figs. 8 and 9, in which it will be seen that the cover L', is stretched over the seat and then tucked around its edges the 95 back piece g, of the cantle being afterward sewed on by removing the back tacks when the cover L', is dry. This is a very tedious operation and a cover cannot be fitted so snugly to the seat as by the employment of 100 my invention.

Having thus described my invention what I claim as new and desire to secure by Letters Patent, is,

1. The employment of an elastic bed or cushion D, in combination with the cover and seat J, substantially as and for the purpose herein shown and described.
- 5 2. The arrangement and combination of the box B, adjustable sliding bars E, elastic cushion D, seat J, clamp K', and pressing lever G, as and for the purpose herein shown and described.

JOHN MACLURE.
